OVEN BURNER

Henry J. Karges and George J. Zurstadt, Evansville, Ind., assignors to Indiana Stove Works, Evansville, Ind., a Corporation of Indiana

Application August 13, 1931. Serial No. 556,854

1 Claim. (Cl. 158—104)

This invention relates to improvements in oven burners and the manner of installing the same in conjunction with gas stoves used in apartment houses of the high-oven type, sometimes called "elevated oven", and the low-oven type, sometimes called "four-hole cooker", or "three-hole cooker", as well as all other baking and broiling ovens for gas stoves which must be placed in small space and, therefore, especially designed 5 and adapted for apartment house kitchenettes.

The invention has for some of its objects the provision of a burner for the ovens of gas stoves of the indicated character, whereby to produce a better and improved distribution of the heat 10 in the oven; to permit a maximum amount of air to reach the flame of each porthole to improve combustion and thus increase the thermal efficiency of the burner and oven; to construct the burner so that the gas connections for the 15 burner may be made interchangeable for either the right-hand side or the left-hand side of the oven, and also interchangeable for either the front part or rear part of the oven before the 20 gas portholes are drilled in the burner; and to provide means connected with the burner in 25 such a manner that the gas feed pipe will be concealed, and further enabling the association of the control valve for the oven burner with the valves for the cooking burners so that it may 30 be easily located and be conveniently accessible.

The nature of the invention and its distinguishing features and advantages will appear when the following specification is read in connection with the accompanying drawing, in which—

35 Figure 1 is a fragmentary section of a gas stove of the elevated oven type, selected to illustrate a burner installed in the oven thereof, in accordance with the invention;

Figure 2 is a perspective view of the burner 40 detached, the same being shown inverted;

Figure 3 is a transverse section on the line 3—3 of Figure 2.

The gas stove 10, as illustrated in Figure 1, includes an elevated oven 11 and a gas manifold 45 12, to which the usual control valves are directly connected at the front of the stove at the base thereof. The oven of the type of stove shown is subdivided by a removable bottom oven plate 13. in the baking oven section, which is shown at 14. The tins or pans and the like which contain the goods to be baked or roasted are placed on shelves 50 or racks in the upper section of the oven, above the removable bottom oven plate. The lowermost space of the oven serves to receive the 55 goods to be broiled and toasted. It is in the

lowermost space or, in other words, the bottom of the oven in which the burner 14 of the present invention is positioned. It is to be understood that the gas connections to the burner 14 may be positioned at the left or the right, or 60 toward the front or rear of the oven, wherever it is most convenient to make the gas connection, also in order to have the benefit of as much space as possible and thereby permit the use of 65 a relatively wide broiler pan.

The burner 14 is of a single strand type, substantially of rectangular shape. The burner consists of a hollow elongated element closed at the ends and having flat top and bottom walls 15 and 16, respectively, which are joined at the opposite side by relatively angularly disposed walls 17 which provide the burner with beveled sides. The burner has two apertured or slotted ears 18 on each end in the present instance, although there may be provided two such ears on one end and 70 one each on the opposite end for attaching, securing or suspending the burner from brackets or the like on the side walls of the oven. Each of the ears may be scored so that those not wanted 75 may be broken off. The burner in the present instance is shown positioned in the oven 11 extending lengthwise between the sides thereof. The ears on the ends of the burner are each attached as at 19 to a bracket 20 secured to the 80 related side wall of the oven.

The burner is provided with portholes 21 for the outlet of streams or jets of gas. The portholes occur in the burner so as to direct the streams or jets of gas laterally downward for best results. The portholes, therefore, will be 85 drilled in those walls 17 which when the burner is in position will face downwardly. This drilling is done after the position of the burner is determined. Any arrangement of portholes in each angularly disposed wall 17 may be provided, and in the instant case there is one row in each of the downwardly facing walls 17. By providing the burner with top and bottom flat walls having flat outer surfaces, the burner may repose on a flat support, while the portholes are being 90 drilled, which is a distinct advantage. The burner is provided with laterally extending gas inlet means 22 on one end, the same being in the form of a tubular extension which is tapped as at 23.

The gas connections leading from the manifold 11 consist of a gas feed pipe 24 which extends rearwardly, then upwardly behind the back wall 25, then forwardly through the wall 25 and then 95 upwardly into the oven at one side wherein it is 100 105 110

fitted to an air regulator 26 connected by a goose-neck 27 in threading engagement with the tapped end 23 of the inlet 22 of the burner. It will be apparent that the feed pipe 24 will be practically concealed. The feed pipe has connected therein a control valve 28 to control the flow of gas to the burner. The valve 28 is arranged adjacent the manifold in line with the other valves for the cooking burners and, therefore, will be conveniently accessible.

From the foregoing it will be apparent that there has been described a gas stove equipped with an oven burner to which gas is fed from underneath the oven at one side affording a maximum of space for a relatively large broiler pan; that by providing the goose-neck it is possible to have the air regulator 26 in a convenient position for adjusting it to regulate the supply of air entering the burner through the bottom of the oven; that the gas to the burner may be controlled from the front of the stove below the oven enabling a person standing at the front of the stove

to turn on the gas and instantly ignite it as it issues from the burner; that the flat top and bottom of the burner permits spreading out the burner to such an extent as to separate the two rows of gas flames to a maximum distance, thereby improving the distribution of heat in the gas oven; and that by reason of the construction of the burner 14 a maximum amount of air may reach the flame of each porthole improving the combustion.

We claim:

An oven gas burner consisting of a hollow elongated burner element comprising flat top and bottom walls joined by relatively angularly disposed side walls, each of certain of said side walls being apertured to discharge the gas laterally downward, at opposite sides of the burner, said element having laterally extending gas inlet means on one end thereof, and means integral with the element for attaching it.

HENRY J. KARGES.
